Primary Examiner — Marianne Pandozzi*Assistant Examiner* — Jae Liang(74) *Attorney, Agent, or Firm* — Loeb & Loeb LLP**CLAIM**

The ornamental design for a surface design for household appliance or utensil, as shown and described.

DESCRIPTION

FIG. 1 is a perspective view of a surface design for household appliance or utensil showing my new design; and, FIG. 2 is an in use front elevational view thereof. The broken line showing in the figure drawings are included for the purpose of illustration and form no part of the claimed design.
